CLAIM

The ornamental design for a perfume bottle, as shown and described.

DESCRIPTION

FIG. 1 is a perspective view of a perfume bottle of the new design;

FIG. 2 is a bottom plan view thereof;

FIG. 3 is a front elevational view thereof, the rear, left side, and right side elevational views being identical except for the unclaimed dispensing tip; and,

FIG. 4 is a top plan view thereof.

The broken lines shown in the drawings are for illustrative purposes only and form no part of the claimed design.

The stippled shading shown in the drawings represents a contrasting surface.
